UNITED STATES PATENT OFFICE.

HYLA F. MAYNES, OF NORTH TONAWANDA, NEW YORK, ASSIGNOR OF ONE-HALF TO
EMMA C. MAYNES, OF NORTH TONAWANDA, NEW YORK.

KNOCKDOWN SUPPORT.

Application filed June 25, 1927. Serial No. 201,323.

This invention relates to knock down supports, particularly those which must be repeatedly put up and taken down and which must be capable of supporting substantial 5 and often moving loads.

Such supports are particularly useful in connection with portable amusement rides. These rides when forming part of traveling shows and carnivals must be repeatedly set 10 up and knocked down, so that it is important not only that the supports have the necessary strength and rigidity but that they may be set up and knocked down with the least labor and within the shortest space of time consistent with safety. It has heretofore been 15 the practice to make these supports of steel piping articulated by means of machined bed clamps, each joint being carefully fitted and the elements intended to be assembled always 20 in the same relation. This has necessitated the marking of every element and has made it impossible to set up the ride with any speed. Furthermore, in setting up and knocking down the ride it has been necessary 25 to apply hammer blows to the jointed ends of the elements themselves which has often resulted in breaking or injuring them.

It is the object of the present invention to 30 make a knock down support free from these objectionable features. This I have done by doing away with the necessity for a nice fit between the elements and securing a tight joint by means of separate wedge pins. Each upright is provided with one or more 35 horizontally projecting yokes, either single or double, and each horizontal element with castings provided with openings which fit over the yokes. The horizontal elements are then clamped to the uprights by inserting 40 the wedge pins within the outer ends of the yokes. As a result all elements of the same kind and dimensions can be made interchangeable, no time need be lost in searching for a particularly numbered piece, and the 45 hammer blows necessary in assembling and disassembling are applied to the wedge pins and not to the elements themselves, which prolongs the life of the elements.

In the accompanying drawings I have illustrated a preferred embodiment of my invention. In these drawings Figure 1 is a fragmentary plan view of a section of a curved ride provided with the knock down support of the present invention; Figure 2 55 is an enlarged detail partly in section show-

ing three uprights, each provided with a double yoke, and two intermediate horizontal elements supported thereby, the uprights being arranged on a curve as in Figure 1; Figure 3 is a section taken along line 3—3 60 of Figure 2 showing the manner in which the wedge pins clamp the horizontal elements against the uprights; Figure 4 is a perspective view of one of the joints showing the wedge pin in place; Figure 5 is a perspective 65 view illustrating one upright and horizontal element in position just prior to assembly; Figure 6 is an elevation of an assembled section of the support; Figure 7 is a view similar to Figure 3 showing the uprights in 70 alignment; Figure 8 is a detail of one of the joints showing a modified form of pipe lock or clamping element, this form differing from the one shown in Figure 7 to permit the horizontal elements to be mounted in 75 alignment; Figure 9 illustrates two right-angle joints made in accordance with the present invention, Figure 10 is an elevation of one of the joints shown in Figure 9 looking in the direction of the arrows 10—10, 80 and Figure 11 is a view similar to Figures 7 and 8, but showing an upright crossed by a single horizontal element and provided with a single yoke.

The supports illustrated in these drawings 85 comprise a plurality of uprights 1 consisting of sections of cylindrical steel piping, and horizontal elements 2, also consisting of sections of steel piping, supported upon and secured to the uprights. The uprights 1 are 90 mounted upon standards 3 designed to rest upon the ground. In order to compensate for inequalities in the surface of the ground, these standards are made adjustable by means of telescopic connections, not illustrated. The present invention relates to the 95 means by which the horizontal elements are secured to the uprights, and these means I shall now describe.

Each upright is provided with one or more 100 yokes 4. These yokes are made of cast steel and, as illustrated most clearly in Figures 3 and 4, consist of a collar 5 which encircles the upright and is welded thereto, and one or a pair of projecting ears, or yokes proper 105 6. Each horizontal element 2 is provided, either at its ends or intermediate its length, with a cast steel pipe lock 7 consisting of a collar 8 welded to the pipe and a vertical clamping element 9 having a cylindrical face 110

11 pierced by an opening 12 adapted to receive one of the projecting parts of the yoke. In assembling the parts, the opening 12 in one of the pipe locks is slipped over a 50 projecting ear of a yoke until the face 11 bears against the upright. The yoke 6 then projects beyond the pipe lock and into it a wedge pin 13 is inserted and driven against the outer face of the pipe lock, thus clamping 10 the latter against the upright. The position of the parts before assembly is shown in Figure 5, and after assembly in Figures 3 and 4.

As most amusement rides are curvilinear, 15 the uprights are commonly arranged on a curve as illustrated in Figures 1 and 2. In order that the horizontal elements shall be interchangeable, the cylindrical clamping faces of the pipe locks are made less than 180° in extent, as illustrated most clearly in Figure 2, and in order that each yoke shall be normal to the horizontal element which it supports, the two ends of each yoke are set at the proper angle, as illustrated clearly in Figure 2. All uprights therefore having the 20 same number of yokes, although interchangeable, must be set so that each projecting ear of each yoke is always normal to the horizontal element supported by it. In the case of 25 a straight ride, or a straight section of a ride, the ears of the yokes are aligned with each other, as illustrated in Figures 7 and 8, and in such cases the cylindrical clamping faces are exactly 180° in extent, and the pipe 30 locks made so that succeeding elements continue in the same straight line.

The horizontal elements, illustrated in Figures 2 and 7, are arranged with their piping on alternate sides of the center line 40 of the uprights. By varying the shape of the pipe locks, as illustrated in Figure 8, the piping can be made coaxial when assembled.

In Figure 9 I have illustrated the invention applied to two right-angle turns. The 45 principles involved are precisely the same as in the case of straight or curved sections of the support, but here the two projecting ears of the yokes are situated at right-angles and the pipe locks are, of course, of modified form.

In Figure 11 I have illustrated the use of a single yoke on an upright. Here the pipe lock is intermediate the ends of the pipe and is provided with two collars 8 and a single clamping element 9.

In Figures 1 and 6 I have illustrated other single yokes which support the cross pipes 14 on which the rails 15 are mounted.

The advantages of my improved support 50 will be apparent from the foregoing description. In a straight-away section all of the analogous parts of the same dimensions are interchangeable, both the uprights and the horizontal elements. The horizontal elements are not only interchangeable end to

end, but can be applied to either side of the line of uprights. That is, they may be reversed end for end and top for bottom. In the case of a curved ride it is necessary to position the uprights so that the angular 70 disposition of the yokes makes them always normal to the supported elements. Otherwise, all uprights having the same spacing of yokes are interchangeable. Where a right-angle turn is to be made, the uprights 75 are also interchangeable, but must be properly positioned. The horizontal elements are, however, completely interchangeable.

As a result of this complete interchangeability, the operators in setting up the support can utilize the first element of a given kind which they put their hand to and be assured of a tight fit in all cases. The intricate system of numbering interfitting elements is thus done away with and the time required to set up a support greatly reduced. The elements are articulated by inserting the wedge pin after assembly of the parts and driving it in position by means of a hammer blow. The support can be disassembled with even greater ease, the wedge pins being readily knocked out by a blow from the bottom. In the event that any of the pins bind, repeated blows can, at worst, do no more than injure the particular pin which can be easily replaced. None of the elements of the support themselves is subjected to hammer blows and danger of breakage or injury is practically eliminated.

I claim:

1. A knock down support comprising the combination of a plurality of uprights, yokes on the uprights, a plurality of interchangeable horizontal elements each terminating in a member provided with an opening for receiving the yoke, and wedge pins adapted to enter the yokes and lock the horizontal elements in position upon the uprights.

2. In a knock down support the combination of an upright, a horizontally projecting yoke thereon, a horizontal element, a casting thereon having a face for receiving the upright and an opening for receiving the yoke, and a wedge for entering the yoke to clamp the casting against the upright.

3. In a knock down support the combination of a cylindrical upright, a double horizontally projecting yoke thereon, a pair of horizontal elements each terminating in a casting having a cylindrical concave face adapted to fit partly around the upright and an opening adapted to receive one of the projecting parts of the yoke, and wedge pins adapted to enter the yoke and clamp the castings against the uprights.

4. A knock down support for amusement rides comprising the combination of a plurality of interchangeable uprights arranged on a curve, a double horizontally projecting

yoke on each upright, a plurality of interchangeable horizontal elements each terminating at either end in a casting having a cylindrical concave face of less than 180° in extent fitting partly around one of the uprights and an opening receiving one of the projecting parts of one of the yokes, and wedge pins within the yokes clamping the horizontal elements against the uprights.

10 5. A knock down support for amusement rides comprising the combination of a plurality of interchangeable uprights arranged on a curve, a double horizontally projecting

yoke on each upright, a plurality of interchangeable horizontal elements each terminating at either end in a casting having a cylindrical concave face of less than 180° in extent fitting partly around one of the uprights and an opening receiving one of the projecting parts of one of the yokes, each 15 projecting part of each yoke being normal to the horizontal element which it supports, and wedge pins within the yokes clamping the horizontal elements against the uprights.

In testimony whereof I affix my signature.

HYLA F. MAYNES.
